UNITED STATES PATENT OFFICE.

ALTUS T. HAUSER, OF ELLENSBURG, WASHINGTON.

CONVERTIBLE HAIR-CUTTER AND SAFETY-RAZOR.

1,077,530.

Specification of Letters Patent.

Patented Nov. 4, 1913.

Application filed October 10, 1912. Serial No. 725,004.

To all whom it may concern:

Be it known that I, ALTUS T. HAUSER, a citizen of the United States, residing at Ellensburg, in the county of Kittitas and 5 State of Washington, have invented certain new and useful Improvements in Convertible Hair-Cutters and Safety-Razors, of which the following is a specification.

This invention relates to hair cutters and 10 safety razors and my object is to produce a device of this character to be handled as a safety razor or a hair cutter, a further object being to produce an implement which can be quickly converted from one use to the 15 other and which is of simple and inexpensive construction.

With these objects in view, the invention consists in certain novel features of construction as hereinafter described and 20 claimed.

Referring to the accompanying drawings in which similar reference characters refer to similar parts—Figure 1 is a top plan view of the comb and razor case; Fig. 2, 25 an end view of the same doubled upon itself in operative position; Fig. 3, the same with a razor blade inserted in the holder; Fig. 4, a side elevation of Fig. 3 showing the comb side of the device; and Fig. 5, a like view 30 of the opposite or razor side of the same.

In the said drawing, 1 is a holder, consisting of a plate bent to form an arched top 2, walls 3 and 4 formed with depending teeth 5, wall 3 being bent upon itself at 6 35 to form a resilient guard 7 provided with roughened adjacent surfaces 8 on either side of the depending teeth 5 adapted to receive a razor blade 9. A pair of lugs 10 engage corresponding slots 11 in the wall 3 and 40 bind the razor blade between the guard 7 and the wall 3.

The holder 1 is bent upon itself to form an arch essentially semi-cylindrical which is provided with heads 12 formed with the 45 wall 4 having lugs 13 engaging the inner surface of the holder 1 centrally of the arched top 2 to limit the bending movement of the wall 3 with relation to the wall 4 and a section 15 of their periphery unattached for a purpose hereinafter more fully described. The guard 7 is provided with a handle 16 for the convenience of the user. The teeth 5 on the comb side of the device are cut through the wall of the holder in 50 the usual manner and in the wall 3 slits are

cut longitudinally of the holder and the resilient guard 7 to provide a series of double teeth when the guard is folded upon the wall 3, between which is inclosed the razor blade 9 which is removably clamped by the 60 lugs 10 in engagement with the roughened surfaces 8 when said lugs are brought into engagement with the slots 11.

If it is desired to use the device for cutting hair, the razor blade is inserted between the guard 7 and the wall 3, the guard is closed against the wall, the lugs 10 engaging the slots 11, the wall 3 resting resiliently against the unattached section 15 of the heads 12 and the teeth 5 of the member 4 70 are employed as an ordinary comb. On pressing the wall 3 upon wall 4 the razor blade 9 is in a position to engage the hair which will project through the teeth 5 of the comb and the teeth 5 adjacent the blade, 75 upon the application of the device to the hair as in the operation of combing, and engage the blade 9, thereby cutting the hair.

When it is desired to use the device as a razor the guard 7 is laid adjacent the surface to be shaved and the beard or other hair projecting between the teeth 5 of the guard and the adjacent plate 3 will be cut in the usual manner.

It has been found that when using my device as a razor that the best results are obtained with the sliding diagonal stroke across the beard and sides of the face. By such movement a hair engaging one of the teeth of the guard will, upon the continued 90 downward movement, slip between said tooth and into the opening formed between it and the adjacent tooth and engage the cutting edge of the blade and consequently be cut. It is apparent that if the hairs are 95 not shaved on the first stroke, a subsequent stroke will remove them.

From the above description, it will be seen that I have produced a convertible safety razor adapted to be used for shaving or 100 shearing.

Having thus described my invention, what I claim is:—

1. In a combined hair cutter and razor, a holder comprising a single piece of metal bent upon itself, one end thereof provided with depending teeth, the other end thereof outwardly bent upon itself to provide a receptacle for the razor blade and provided with teeth adjacent to the bottom of the re- 105

110

ceptacle, the cutting edge of said razor blade engaging the inner surfaces of the bent-over portion and the holder.

2. In a combined hair cutter and razor, 5 a holder comprising a rectangular piece of sheet metal bent upon itself semi-cylindrically, the extremities of said holder projecting tangentially therefrom, teeth formed upon the edges of said projecting ends, a receptacle for a razor blade formed with one 10 of said projecting ends, a razor blade mounted in said receptacle and adapted to cut substances engaged by the teeth of said other projecting end, the cutting edge of 15 said razor blade engaging the inner surfaces of the bent-over portion and the holder and extending beyond the inner terminal of said teeth.
3. In a combined hair cutter and razor, 20 a holder bent upon itself semi-cylindrically, closures for the ends of the semi-cylindrical portion formed intermediate the end of said holder, a resilient guard formed at one end thereof by outwardly bending one end of 25 the holders upon itself, teeth formed through both thicknesses of metal adjacent to the line of said bending, roughened surfaces on the adjacent surfaces of said guard and the body of the holder, a razor blade 30 mounted between said roughened surfaces, means for binding said razor blade between said guard and the body of said holder and the cutting edge of said razor blade engaging the surfaces of the bent-over portion 35 and the holder and extending beyond the inner terminals of said teeth, a handle formed with said guard, depending teeth formed with the opposite end of said holder and adapted to coöperate with said razor 40 blade in the process of cutting the hair.

4. In a combined hair cutter and razor, a substantially semi-cylindrical holder, heads at the opposite ends thereof, wings formed by the tangential extension of the 45 cylindrical walls, depending teeth formed on the edges of said wings, a pocket adapted to hold a razor blade formed integral with

one of said wings and the inner wall of said socket provided with openings, a razor blade in said pocket, means for clamping 50 said blade in the pocket including downwardly extending lugs formed on the inner surface of the outer wall of said pocket and adapted to extend through said openings in the inner wall of said pocket and engage the 55 back of said razor blade, said pocket adapted to resilient coöperation with the teeth formed on the extremity of the opposite wing.

5. In a combined hair cutter and razor, 60 a semi-cylindrical holder formed of a single sheet of metal, outwardly extending wings integral with said holder, one of said wings provided with longitudinal slots adjacent one end thereof, and bent centrally of the 65 slots back upon itself convergent of the outwardly extending portion to form a pocket, said slots forming teeth at the outer extremity of said wing, teeth formed at the extremity of the other wing and the inner 70 wall of said pocket provided with openings, closures for the semi-cylindrical portion formed integral with the holder intermediate its ends, a razor blade adapted to be fitted within the pocket aforesaid, means 75 for holding said razor blade within said pocket, including lugs formed on the outer wall of said pocket adapted to engage the back of said blade and extend through the openings in the inner wall of the pocket, a 80 handle formed integral with the outer wall of said pocket, the cutting edge of said razor blade engaging the inner surfaces of said pocket and extending beyond the inner terminal of said teeth, and said pocket adapted 85 to resilient coöperation with the teeth formed on the extremity of the opposite wing.

In testimony whereof I affix my signature in presence of two witnesses.

ALTUS T. HAUSER.
